UNITED STATES PATENT OFFICE

FRANK H. TREGO, OF NEW YORK, N. Y., ASSIGNOR, BY MESNE ASSIGNMENTS, TO RALPH C. COXHEAD CORPORATION, OF NEW YORK, N. Y., A CORPORATION OF DELAWARE

PAPER GUIDING AND GAUGING MEANS

Application filed October 15, 1929. Serial No. 399,733.

This invention relates to improvements in typewriting machines and more particularly to paper guiding and gauging means.

An object of the invention is to guide the work sheet vertically between the type carrier or shuttle and the printing hammer so as to present it properly to the types.

In carrying out the invention there is provided a rack supported on the carriage above the printing means. It is provided with one or more channel shaped guides to hold the work sheet in its vertical position.

A scale bar is pivotally supported on the paper rack which may be swung to a position where it may assist in locating the paper guides relatively to the letter space position on the carriage. The scale bar may be swung to another position to serve as an extension of the paper rack.

20 The paper rack is pivotally supported on the carriage so that it may be swung rearwardly to lay the work sheet on an erasing shelf located behind the vertical plane in which the work sheet is fed to and from the printing point. Stops are provided to limit the movement of the paper rack to its various positions where it is held by suitable detents.

25 The paper rack comprises two vertical end pieces and three horizontal bars connecting said end pieces; the paper guides being supported on the middle one of the horizontal bars and are prevented from rotation about said middle bar by the other two bars.

30 Other features and advantages will herein-after appear.

In the accompanying drawings,

Fig. 1 is a front elevation of a portion of the carriage showing the invention applied thereto;

Fig. 2 is a sectional view of the carriage and the paper rack;

Fig. 3 is a front view, partly in section, of one of the paper guides;

45 Fig. 4 is a sectional view taken on the line 4-4 of Fig. 3;

Fig. 5 is a side elevation of a portion of the carriage and the paper rack with the scale in position to adjust the paper guides;

50 Fig. 6 is a view similar to Fig. 5 showing

the paper rack swung back to lay the work sheet on the erasing shelf;

Fig. 7 is a detail sectional view taken on the line 7-7 of Fig. 5; and

Fig. 8 is a view of the blank from which either paper guide may be formed.

Similar characters refer to similar parts throughout the several views.

The invention is shown as applied to a varityper writing machine which includes a carriage 10 to travel back and forth on a rail 11 secured to the main frame (not shown); the carriage being guided at its upper end by a bar 12, secured to end pieces 13 of the carriage.

55 A work sheet 14 may be fed up from a container 15 by feed rollers 16 and 17 to advance it between a printing hammer 18 and a type carrier or shuttle 19. The hammer 18 is arranged behind the work-sheet and is 60 adapted to co-operate with types 20 of the type shuttle 19; the shuttle being indexed to select the type in the usual manner by means including an actuator 21 operated by the character keys, not shown.

65 To hold the work sheet there is provided a paper rack, indicated generally by the numeral 22, which includes two side pieces 23 and 24 secured to each other by horizontal rods or bars 25, 26 and 27. Each one of the side pieces 23 and 24 is supported on a shouleder stud 28, Figs. 1 and 7, secured to the carriage end 13 by a nut 29.

70 Supported on the middle bar 26 are two guides 30 and 31 one at each side of the work sheet 14. Each guide has a portion 32 bent up from its side edge to form a groove 33 in which the work sheet is guided. The guides 30 and 31 are adjustable lengthwise or axially on the bar 26 according to the width of the work sheet and according to the position of the sheet lengthwise of the carriage.

75 Each side guide is supported on the bar 26 by two ears 34^a bent rearwardly therefrom. A friction spring 34^b (Fig. 4) is provided to hold the paper guide against accidental lateral displacement on the bar. Said spring is located between the two ears 34^a and between the back 34 of the paper guide

80 85 90 95 100 and the rod 36. It is held in place horizon-

tally and vertically by two ears 34^a bent therefrom and extending into two apertures 34^a in the paper guide, Figs. 3 and 4. This arrangement, it will be understood, permits 5 the guide to be readily adjusted axially of the supporting bar 26. The upper bar 25 and the lower bar 27 prevent rotation of the paper guide about the bar 26 or in other words, hold it in a vertical position.

10 The web 33^a of the paper guide, which joins the portion 32 with the body part 34, is of considerable length and may be used to square a fresh work sheet in the machine. The usual stationary line guides 35 may be 15 used to position a work sheet in the machine at the printing line.

An erasing shelf or table 36 is supported on the carriage over which the work sheet may be laid when an erasure is to be made. 20 Said erasing shelf is located behind the plane in which the work sheet is normally disposed. Consequently to lay the work sheet on the erasing shelf the paper rack 22 may be swung rearwardly about its pivots 28 to 25 the position in Fig. 6.

Stops 40 and 41 on each of the rack ends 23 and 24 engage a stud 42 on the carriage ends 13 to limit the movement of the paper rack 22 to its active or inactive position, Figs. 30 35 and 6. To hold the paper rack in either of these positions there is secured to each end thereof a detent spring 44 engaging a corner 45 of rectangular head 46 on the pivot stud 28.

35 To assist in positioning the paper guides 30 and 31 at the desired letter space position on the carriage, there is provided a scale bar 50 secured to two arms 51 and 52 pivoted on shouldered screws 53 and 54 at the upper 40 end of the paper rack 22. During typing operations the scale bar 50 occupies a raised position as in Fig. 2 where it serves as an extension of the paper rack and where it 45 is held against falling rearwardly by fingers 55 bearing against the ends 23 and 24 of the paper rack. The scale bar may be swung from the position in Fig. 2 to the position in Figs. 1 and 5 in front of the work 50 sheet 14, where it may be arrested by the downward extensions of the backs or body parts 34 of the paper guides, and where it may be used to locate the paper guides in the desired letter space position. The scale 55 50 may also be used to position the carriage with reference to a pointer 56 arranged in the vertical transverse plane of the printing point to locate the carriage in any letter space position at the printing point. It may also 60 be used to center a word on the work sheet as follows: Let it be assumed that the writing line begins at 5 and terminates at 55 on the scale. This includes fifty spaces the half of which is twenty-five spaces. This 65 number of spaces (25) added to letter space

at the beginning of the line makes 30 which is the center of the writing line. Having once determined the center of the writing line the starting point of any word or group of words may readily be determined by subtracting from this position (30) half the number of letter spaces in the word to be centered on the work sheet.

70 The portions 32 of the paper guides are curved rearwardly at their upper ends 52 to direct the work sheet rearwardly towards the scale bar 50 as indicated in Fig. 2. If desired the work sheet may be conducted behind the scale bar.

75 It should be understood that the paper guides 30 and 31 are formed or bent up from identical blanks 60 like that shown in Fig. 8, the ears 34^a of the guide 30 being bent from the side edges of the back portion 34 and in the opposite direction to those on the guide 31. Similarly the side members 33^a are bent in opposite directions from the back members 34 and the front members 32 are also bent in opposite directions from the side members 33^a of the two guides.

80 It will be understood that irrespective of the position of the scale bar, it is moved back with the paper rack as indicated in Fig. 6 when the latter is swung to its ineffective position.

85 Variations may be resorted to within the scope of the invention.

I claim:

1. In a typewriting machine, the combination of printing means including settable types and a hammer to co-operate therewith, a carriage, feed rollers on said carriage and located below the printing means to feed a work sheet between the types and said hammer, means including a channel shaped guide to embrace the side edge of the work sheet to guide it vertically from the feed rollers to the printing means, means to support said guide on said carriage, a scale on said carriage to assist in locating the guide lengthwise of the carriage, and means whereby said scale is shiftable into co-operative relation with said guide, the movement of said scale being limited by said guide.

100 2. In a typewriting machine, the combination of printing means including settable types and a hammer to co-operate therewith, a carriage, feed rolls on said carriage and located below the printing means to feed a work sheet between the types and said hammer, a frame above the printing means, a guide for the work sheet supported on said frame, and a scale pivotally supported on said frame so that it may be swung from an ineffective position to a position in front of said guide, said guide being adjustable laterally on said frame to the desired letter space of the carriage with reference to said scale.

3. In a typewriting machine, the combination of printing means including settable types and a hammer to co-operate therewith, a carriage, feed rolls on said carriage and located below the printing means to feed a work sheet between the types and said hammer, a frame above the printing means, a guide for the work sheet supported on said frame, and a scale pivotally supported on said frame so that it may be swung to a position for adjusting the paper guide, said scale being also swingable to a position where it serves as an extension of said frame to assist in guiding the paper.
4. In a typewriting machine, the combination of printing means, a carriage, means on said carriage to guide a work sheet, and a scale pivotally supported on the carriage so that it may be swung to a position in front of the guiding means to assist in locating the guiding means lengthwise of the carriage, the movement of the scale to its ineffective position being limited by the guiding means.
5. In a typewriting machine, the combination of printing means, a carriage, a frame on said carriage, a paper guide on said frame, and a scale-bar pivotally supported on said frame so that it may be swung to a position where it may assist in locating the paper guide at the desired letter spacing position, said scale-bar being swingable to another position to serve as an extension of said frame to assist in guiding the work sheet.
6. In a typewriting machine, the combination of printing means including settable types and a hammer to co-operate therewith, a carriage, feed rolls on said carriage and located below the printing means to feed a work sheet between the types and said hammer, means located above the printing means to guide a work sheet vertically therefrom, an erasing shelf arranged and located in a plane between the printing means and the paper guiding means and behind the plane in which the work sheet is normally guided, and means to pivotally support the paper guiding means that it may be swung rearwardly so that the work sheet may rest against the erasing shelf.
7. In a typewriting machine, the combination of printing means including settable types and a hammer to co-operate therewith, a carriage, feed rollers on said carriage and located below the printing means to feed a work sheet between the types and said hammer, means located above the printing means to guide a work sheet vertically therefrom, an erasing shelf located in a plane extending horizontally between the printing means and the paper guiding means and arranged behind the plane in which the work sheet is normally guided, the work sheet guiding means including a frame on said carriage, and a paper guide on said frame to embrace the side edge of the work sheet, and means to pivotally support said frame on the carriage so that it may be swung rearwardly at its upper end to lay the work sheet on the erasing shelf.
8. In a typewriting machine, the combination of printing means including settable types and a hammer to co-operate therewith, a carriage, feed rolls on said carriage and located below the printing means to feed a work sheet between the types and said hammer, means located above the printing means to guide a work sheet vertically therefrom, an erasing shelf arranged and located in a plane between the printing means and the paper guiding means and behind the plane in which the work sheet is normally guided, means to pivotally support the paper guiding means that it may be swung rearwardly so that the work sheet may rest against the erasing shelf, a stop to arrest the paper guiding means in either position, and a detent to hold the paper guiding means against said stop.
9. In a typewriting machine, the combination of printing means including settable types and a hammer to co-operate therewith, a carriage, feed rolls on said carriage and located below the printing means to feed a work sheet between the types and said hammer, a paper rack on said carriage to hold the work sheet properly relatively to the printing point, said rack including two end pieces, three horizontal bars connecting said end pieces, a paper guide adjustably supported on the middle one of the horizontal bars, the other bars preventing rotation of the paper guide about its supporting bar, and means to support said rack on said carriage by the lower portion of its end pieces.
10. In a typewriting machine, the combination of printing instrumentalities to print at a common point, a carriage, means on said carriage to feed a work sheet upwardly with reference to the printing point, a paper guide supported on the carriage and vertically disposed above the printing line, said guide being formed from a single piece of sheet metal, and comprising a rear member, and a front member, the rear member having a projection at its lower end extending beyond the lower end of the front member, and a scale pivotally supported on the carriage so that it may be swung from an ineffective position to an effective position under the lower edge of the front member of the paper guide and against the extension of the rear member of the paper guide.
11. In a typewriting machine, the combination of printing instrumentalities to print at a common point, a carriage, paper feeding means on said carriage, means to guide the work sheet vertically above the printing point, a scale pivotally supported on the carriage so that it may be swung from an ineffective position to an effective position in

front of the work sheet, and a pointer at the printing point to co-operate with said scale to locate the carriage in any letter space position.

- 5 12. In a typewriting machine, the combination of printing instrumentalities to print at a common point, a carriage, paper feeding means on said carriage, work sheet guiding means above the printing point, an erasing shelf located behind the work sheet and at a lower level than the guiding means, and means whereby the guiding means may be actuated to lay the work sheet over the erasing shelf for the purpose of erasing.

- 10 13. In a typewriting machine, the combination of printing instrumentalities to print at a common point, a carriage, paper feeding means on said carriage, work sheet guiding means above the printing point, an erasing shelf located behind the work sheet and at a lower level than the guiding means, means whereby the guiding means may be actuated to carry the work sheet against the erasing shelf, means to arrest the actuating means in either of its positions, and means to hold the actuating means in either of its positions against accidental shifting.

- 15 14. In a typewriting machine, the combination of printing instrumentalities to print at a common point, a carriage, means on the carriage to feed a work sheet upwardly relatively to the printing point, a paper rack supported on the carriage, said rack comprising two vertically disposed end pieces, a plurality of horizontal bars extending from one end piece to the other, a paper guide supported on one of said bars, pivot studs secured to said carriage and by which the paper rack is supported on said carriage through the medium of its end pieces so that it may be swung rearwardly, and a detent spring on one of said end pieces and engaging the associate stud to hold the paper rack in its forward position.

- 20 15. In a typewriting machine, the combination of printing instrumentalities to print at a common point, a carriage, means on the carriage to feed a work sheet upwardly relatively to the printing point, a paper supporting rack supported on the carriage, a letter space scale pivotally supported on said paper rack so that it may be swung to an ineffective position, and means to limit the movement of said scale to its ineffective position, the scale in its ineffective position forming an extension of the paper supporting rack to assist in supporting the work sheet.

- 25 16. In a typewriting machine, the combination of printing instrumentalities to print at a common point, a carriage, means on the carriage to feed a work sheet upwardly rela-

tively to the printing point, a paper rack supported on the carriage, said paper rack extending upwardly on said carriage, a scale located in front of the work sheet and above the printing line, two upwardly extending arms by which the scale may be pivotally supported at the upper end of the paper rack so that said scale may be swung upwardly away from the work sheet to an ineffective position, and means to limit the movement of said scale to its ineffective position.

30 17. In a typewriting machine, the combination of printing instrumentalities to print at a common point, a carriage, feed rollers on said carriage to feed a work sheet relatively to the printing point, an upwardly extending paper rack supported on the carriage, said rack comprising two end pieces, and three horizontal bars connected at their opposite ends to said end pieces, paper guides supported on the middle bar of said paper rack, the other two bars preventing rotation of said guides on their supporting bar, an erasing shelf behind the work sheet, studs at the lower ends of the end pieces to pivotally support the paper rack on the carriage so that the latter may be swung rearwardly to carry the work sheet against the erasing shelf, means to limit the rearward movement of said paper rack, a scale located above the printing line and in front of the work sheet, and two arms by which the scale may be pivotally supported at the upper end of the paper rack so that it may be swung away from the work sheet so as not to interfere with an erasing operation, and means to limit the movement of the scale relatively to the paper rack.

35 18. In a typewriting machine, the combination of printing instrumentalities, a carriage, an erasing shelf on said carriage, means including a frame arranged above the printing point to guide a work sheet, means to pivotally support the frame on said carriage so that the work sheet may be laid over the erasing shelf thereby, and a detent to hold the frame.

40 19. In a typewriting machine, the combination of printing instrumentalities, a carriage, a paper guide frame, studs to pivotally support said guide frame on the carriage about which said guide frame may be swung, each stud having a shank by which it may be secured to the carriage, and an enlarged portion at the end of shank, the rack being pivotally supported upon the enlarged portions, a head beyond the enlarged portion of one of said studs, and a detent spring associated with said head to prevent accidental movement of said rack about said studs.

FRANK H. TREGO.
